UNITED STATES PATENT OFFICE.

HARRY M. MANNHEIMER, OF ST. LOUIS, MISSOURI.

GAME APPARATUS.

1,263,334.

Specification of Letters Patent. Patented Apr. 16, 1918.

Application filed March 13, 1915. Serial No. 14,057.

To all whom it may concern:

Be it known that I, HARRY M. MANNHEIMER, a citizen of the United States, and resident of St. Louis, Missouri, have invented 5 certain new and useful Improvements in Game Apparatus, of which the following is a specification containing a full, clear, and exact description, reference being had to the accompanying drawings, forming a part 10 hereof.

My invention relates to improvements in game apparatuses, wherein there is a board bearing the pictorial representation of a passenger coach and the representation of a 15 route of travel for a playing object representing the car, a number of distinguishable sets of objects representing a car for movement over the represented route, passengers for the car, represented pictorially, and motormen, conductors, trackmen, policemen, and the like, together with a deck of cards, 20 certain of which bear numbers corresponding with the number of stations along the route represented, and others bearing directions of plays.

The object of my improvements is to construct a game apparatus which will be instructive, as well as entertaining, and has to do with the handling of passengers and 25 cars, preferably of a street railway system.

With the above purpose in view, my invention consists in certain novel features of construction and arrangement of parts as will be hereinafter more fully described, 30 pointed out in the claims and illustrated by the accompanying drawings, in which—

Fig. 1 shows in plan a game board with certain of the movable objects or men in place, as in the course of playing a game;

Fig. 2 is an edge elevation of the board with certain men thereon;

Fig. 3 is a perspective of a portion of the deck of playing cards showing the consecutively numbered cards;

Fig. 4 is a like view to Fig. 3, showing certain of the cards bearing directions of play;

Fig. 5 illustrates one of the men to be known hereafter in the game as a giant passenger;

Fig. 6 represents a common passenger;

Fig. 7 shows a group of playing objects or men, distinguishable from the passengers;

Fig. 8 shows a group of figures similar to the group shown in Fig. 7, but distinguishable therefrom, as by color; and

Fig. 9 shows an object representing a car.

Referring by numerals to the accompanying drawings:

10 designates the game board, which preferably as shown in Fig. 2, consists of hinged 60 sections.

On one face of the board 10 there is a figure representing a passenger car 11. This figure is preferably made by printing and consists of a diagrammatical plan showing 65 the contour of the car, the arrangement of seats 12, the aisle 13, and certain squares indicated respectively 13^a, 14, 15, 16, and 17, which bear the words "Motorman", "Conductor", "Policeman", "Lone passenger" and 70 "Sand box". Next adjacent the square 13^a appears the characters "10 Pts.", meaning ten points. Next adjacent the square 14 appears the characters "10 Pts." Next adjacent the squares 15 and 17 appear the 75 characters "7 Pts.", and next adjacent the square 16 appears the characters "5 Pts." In the aisle 13 there are a number of squares 18 and next adjacent at least one of the squares are the characters "5 Pts." 80

On the surface of the board 10 adjacent one margin thereof is a square 19 having therein the words "Waiting car", and to one side of the square 19 is a square 20 having therein the word "Destination". Arranged 85 along the remaining free margins of the board are the squares 21, which are numbered consecutively from 1 to 45. Certain of these squares have therein the name of a station or street and next adjacent these last 90 mentioned squares appear the characters "2 Pass.", meaning two passengers, and next adjacent the square numbered 45 appears the characters "End of line-return".

22 designates the playing cards which are 95 hereinafter termed the "numbered" cards, and which bear numbers from 1 to 45, corresponding with the numbers of the squares 21 on the game board.

23 designates the playing cards bearing 100 printed directions of moves for plays in the game, such as "Supply the motorman", "Supply the conductor", "Stop for air—take on four passengers from home". (The home referred to on this last mentioned card 105 refers to the supply of men or playing objects, and is thus indicated in the directions which accompany the game.) "Supply giant passenger to any vacant seat on own side and let one of opponent's passengers change 110 seats to giant's side", "Supply lone passenger", "Two of opponent's passengers to des-

gned", "Two of opponent's passengers to des-

tination", "Track foreman's orders—back car 5 blocks—no move for car", "Supply lady passenger in aisle", "Man gets up, gives seat to lady, takes first place in aisle", 5 "Opponent's first passenger to destination", "Wagon down on track—2 opponent's passengers walk to destination—no move for car", "Track foreman's orders—back car 3 blocks—no move for car", "Behind schedule—go 4 blocks without stop—send opponent's waiting passengers home—no move for car."

The thirteen cards just designated suffice, but I do not wish to limit myself to this 15 number, as it is apparent there is no "suit" and that other direction cards may be found desirable at times but not necessary for purpose of this application.

24 designates a man or playing object 20 which will be hereinafter referred to as a common passenger. These common passengers are in two sets of twenty-nine each, distinguishable from each other. 25 designates a man or playing object which will be hereinafter referred to as a giant passenger, which giant passenger forms the thirtieth object of each set representing passengers. The apparatus comprises only two of these giant passengers, and they are distinguishable from each other, as are the common passengers. 26 designates a playing object or man having thereon the word "Car", and 28 and 29 designate playing objects or men in distinguishable sets, one of 35 each set bearing the word "Motorman", another bearing the word "Policeman", another bearing the words "Lone passenger", another bearing the word "Conductor", and another bearing the word "Trackman".

40 This game may be played by two or four persons, and when played by two persons they are of course opponents, and when played by four persons the players are opposing partners. The cards are all placed 45 in one pack and shuffled in the usual manner, and four cards are dealt to each player, whether there be one, two, three or four persons. The remaining cards of the deck are then placed face down where they may be drawn one at a time by the players. The 50 first player draws a card from the pack and selects the playing object 26 marked "Car" and places it on the square marked "Waiting car 19."

55 He then draws another card from the pack, adds the same to his "hand", and starts the object marked "Car" along the route of travel, by playing one of the numbered cards, or he "passes", as he elects; in 60 any event the "car" should be moved over one division of the route for each play of a numbered card.

Each player thereafter in his turn draws a card before making his play; and each 65 player may at any time in the game "pass"

or decline to play, as is his choice. It is essential that, after the "car" has been moved by a player, as above described, that the player (after each move of the "car") place one of the "passengers" 24 on the specific 70 square which is permanently marked with the numeral corresponding to that of the numbered card just played, and when such numbered card corresponds with a square having thereon a station name, two passengers are placed on said designated square. The car may be moved along after each play, and as it, the car, arrives at a square having a man or passenger such passenger is placed within the car represented on the 80 board unless the card played directs otherwise. If one of the players neglects or fails to move the car after his play, he forfeits the use of two of his passengers.

The play of a numbered card gives the 85 player only one play and one move of the car, but the play of a card having printed directions entitles the player to a second play of a numbered card only and a second move of the car. When the player is unable to follow with numbered card, he forfeits the right to a second play and a second move. The player, however, is required to make second play if able to follow printed card with a numbered card.

90 There is only one "car", and the same, when once started on the route, is sent forward by the players, one "block" (or square, of the series 21) at a "move", until the end of the line is reached, when the car naturally reverses itself and makes a return trip, from the point which is marked on the board with the word "Return". See lower right-hand of Fig. 1.

95 On its return trip the "car" 26 is moved back over the same route, step-by-step, toward the starting point.

The "passengers" 24 are "picked up" by the car as it travels over the route, and are placed on the board in the numbered "car-seats" 21, consecutively, and on the side of the board which corresponds in color to the color of the said "passengers" 24 being picked up.

100 The "passengers", before being placed on the board, are supposed to be at "home", that is—contained promiscuously in a suitable box. (Not shown).

105 The "passengers" which have been placed, as described, on the board, are supposed to be waiting on the street-corners for the "car", and may be termed "waiting" passengers.

110 The "passengers" which are subject to removal from their places on the board, as per the directions on the "direction" cards, must have already secured places on board the car 11.

115 If none of the opponent's "passengers" are aboard the car 11, then the player who 120

holds the "direction" card ordering a removal of a passenger, should retain said direction card for a later play.

When all the "seats" on a player's own 5 side of the car 11 are filled with passengers, he must then play in the space on the board marked "Aisle".

The "giant" passenger 25 counts two (2) points; all other passengers aboard the car 10 11, count one (1) point only; policeman, motorman, etc., count as directed on the "directions" which are printed on the board.

In case any "passenger" of a player is found on a "street" where the "car" 15 26 stops, such passenger should be picked up and placed aboard the car 11, of course.

If any passenger is standing on "streets" which your speeding car 26 "passed", let that passenger wait until said car reaches it 20 on the "return" journey, (if the car returns during the game).

The conductor, motorman, policeman, and sand box, are never to be treated as passengers, and are therefore always "safe" plays; 25 but the giant passenger, lone passenger, and a passenger occupying first place in the aisle, are subject to "removal" from the board and placed in the position described on the "direction" cards such as "Two of 30 opponent's passengers to destination", &c.

When the drawing-deck is exhausted, opposing players will finish their respective hands, until one of the players, or one of the playing partners, is out of cards or 35 "passengers" (men).

Should opposing players, after the drawing-deck has become exhausted, persist in "passing", (neither desiring to make a play), then both will discard their hands, 40 and end the game.

The game as will be seen from the above description is a game of points, which the presence of the playing objects on the board determines. The giant passenger on any 45 seat in the car counts two points. All other passengers aboard car count one point. Motormen, conductors, policemen each count the

points designated on the board; the lone passenger, a track man on the sand box and a passenger on one of the aisle squares 18 50 count the points designated on the board. The game is concluded when either player is out of cards or out of men or out of both cards and men. Passengers waiting along the squares 21 at the conclusion of the game 55 do not count. The player having the greatest number of points, as a matter of course, wins the game.

Having thus described my invention, what I claim as new therein and desire to 60 secure by Letters Patent of the United States therefor, is:

1. An improved game-apparatus, comprising a game-board having thereon a representation of a vehicle with seats for passengers; a route of travel with stations; two sets of playing pieces for movement on said board; a playing piece representing a car to be moved over said route of travel; and two sets of cards for directing the movements of all said last-named playing pieces, one set of said cards being numbered consecutively, and the other set having printed directions for play. 65

2. An improved game-apparatus, comprising a game-board having thereon a representation of a vehicle with seats for passengers; a route of travel with stations represented by squares numbered consecutively; two sets of playing pieces for movement on said board; a playing piece representing a car to be moved over said route of travel; and two sets of cards for directing the movements of all said last-named playing pieces, one set of the cards being numbered consecutively, and the other set having printed directions for play. 70 75 80 85

In testimony whereof, I have signed my name to this specification, in presence of two subscribing witnesses.

HARRY M. MANNHEIMER.
